WILLIAM E. BOEHCK, OF JERSEY CITY, AND HENRY S. GERMOND, JR., OF BAYONNE, NEW JERSEY, ASSIGNEES TO REVOLVATOR COMPANY, OF JERSEY CITY, NEW JERSEY, A CORPORATION OF NEW JERSEY.

PORTABLE ELEVATOR.

1,282,736.

Specification of Letters Patent.

Patented Oct. 29, 1918.

Application filed June 25, 1918. Serial No. 241,816.

To all whom it may concern:

Be it known that we, WILLIAM EDWARD BOEHCK, a subject of the Emperor of Germany, residing at Jersey City, in the county 5 of Hudson and State of New Jersey, and HENRY SHELDEN GERMOND, Jr., a citizen of the United States of America, residing at Bayonne, in the county of Hudson and State of New Jersey, have invented certain new 10 and useful Improvements in Portable Elevators, of which the following is a specification, reference being had to the accompanying drawings.

This invention relates to improvements in 15 portable elevators or tiering machines and particularly to improvements in mechanism by means of which the support of the elevator-base may be readily changed from a rolling support upon wheels to a stationary 20 support upon posts or legs, and vice versa. An object of this invention is to provide a mechanism of the character just referred to which will be simple in construction, comparatively cheap in manufacture and efficient 25 in operation and use.

In the drawings illustrating the principle 30 of this invention and the best mode now known to us of applying that principle, Figure 1 is a side elevation of so much of a portable elevator as is necessary to illustrate this invention and shows the elevator-base as being supported upon wheels; Fig. 2 is a similar view but illustrates the elevator-base as being supported upon legs; Fig. 3 is 35 a front elevation, looking in the direction of the arrow A in Fig. 1; and Fig. 4 is a rear elevation, looking in the direction of the arrow B in Fig. 1, one of the wheels being shown in section. For clearness, the 40 platform is omitted in Figs. 3 and 4.

The base-members *a* support the uprights or standards *b* which are held firmly braced by the inclined bars *c* and within which travels up and down the load-carrying platform *d* controlled by the hoisting cable *e*. Each of the base-members *a* is provided, at 45 its front end, with a supporting post or leg *f* and, at its rear end, with a supporting post or leg *g*; and the elevator is shown, in Fig. 2, supported upon these posts *f*, *g*. The base-members *a* furthermore carry a stationary rear-axle *h* (Fig. 4) on each end *h'* of which there is rotatably mounted an eccentric *i* provided with a radially-extend-

ing crank-arm *j*. Upon each eccentric *i* there 55 is mounted rotatably a wheel *m*. The steering-wheel *n* (Fig. 3) is rotatably mounted in a hanger or bracket *o* the top of which is fastened to one wall *p'* of an L-shaped or angle-iron transverse-member or crosspiece 60 *p* which, as is more particularly described hereinafter, may be rocked or oscillated and which is called by us a "drop-bridge." The tongue *q* is pivotally mounted, at its inner end, in the hanger *o*.

In transverse section, the drop-bridge *p* is in the form or shape of an inverted L and, to each end of that side *p'* which, in the position of the drop-bridge illustrated in Figs. 1, 3 and 4, forms the top or is uppermost, there is fastened rigidly one side of an angle-iron or bracket *p''* forming an end-piece of the drop-bridge *p*. Projecting inwardly from the base-members *a* are a pair of oppositely-disposed pivot-pins *r* which 70 extend into holes *r'* formed in the lower ends (Fig. 3) of the end-pieces *p''* and upon which the drop-bridge *p* may be swung or rocked. The front end of each of the base-members *a* is cut away at the top there- 75 of or formed with a notch or recess *a'*. Just above the hole *r'*, each end-piece *p''* is provided with a stud *s* tapped thereinto, which stud projects outwardly into the notch or recess *a'*. This stud *s* carries pivotally fastened thereon the front end of a link-rod *t* the rear end of which is pivotally secured to the free or outer end of the crank-arm *j* projecting from the eccentric *i*, so that the stud *s* and crank-arm *j* are connected by the link- 80 rod *t*, whereby the drop-bridge *p* is linked to the eccentrics *i*. The bottom wall *a''* of the notch or recess *a'* (that is, the upper edge of the notched front end of the base-member *a*) is flush or even with the top of 85 the front leg *f* fastened to the base-member *a* (Fig. 3); and, when the drop-bridge *p* is rocked on its pivots *r* and the link-rod *t* is thrown back and forth, this bottom wall *a''* serves to limit the throw of the stud *s* and 90 thereby the swing of the drop-bridge *p* and the travel of the link-rod *t*.

In order to swing the drop-bridge *p*, there is provided a bent operating-arm *u* the inner end *u'* of which is mounted free to turn 105 in a bearing *u''* formed in the wall or side *p'* of the drop-bridge *p* (Figs. 1 and 2). To the front end of one of the base-members *a*,

there is fastened a bar w which extends forwardly above the recess a' and in the front end of which there is adjustably mounted a stop-screw x . Upon the inner end u' of the 5 operating arm u , there is fastened a locking-arm y , which engages the stop-screw x , when the operating-arm u is thrown into the position illustrated in Figs. 3 and 1, whereby the drop-bridge p is held locked in the position 10 illustrated in the latter figures.

The operation of the mechanism hereinbefore described will now be readily understood and may be briefly set forth as follows: Let us assume that the machine is in its stationary position (Fig. 2), in which position it rests upon the solid supporting legs or blocks f , g , and that it is desired to render the machine movable upon its wheels m , n . The operator grasps the operating arm u 20 and throws the outer free end of the same upwardly and forwardly, whereby the arm u is brought to the position shown in dotted lines in Fig. 1 and the wall or side p' , which forms the rear wall of the drop-bridge p in Fig. 2, is brought uppermost or into the position of the top wall of the drop-bridge p . In order now to lock the latter in the position shown in Fig. 1, the workman throws the outer or free end of the arm u laterally 25 downward and brings this end substantially parallel with the top of the drop-bridge p (Figs. 3 and 4), during which movement the arm u turns within the bearing u'' and the locking-arm y is thrown into locking engagement with the stop-screw x , thereby locking the drop-bridge p in the position illustrated in Fig. 1. In the position illustrated in Fig. 2, the drop-bridge p rests upon its bottom wall z , which is raised from 30 the floor by the rocking movement just described. The drop-bridge p swings upon the pivots r (Figs. 2 and 3) and the studs s are carried through an arc of a circle and move from the rear end to the front end of 35 the recesses a' , the upper finished edges a'' of the base-members a serving to limit the movement of these studs s (Figs. 1 and 2). In their movement from rear to front, the studs s carry with them the link-rods t , 40 which, in turn, exert a pull on the crank-arms j , resulting in a turning of the eccentrics i , whereby the wheels m are lowered and the posts or legs g are raised. Furthermore, as the drop-bridge p is swung from its 45 position shown in Fig. 2 to its position illustrated in Fig. 1, the steering wheel n is thrown downwardly against the floor and the front ends of the base-members a are raised. By moving the operating arm u 50 in a direction opposite to that just described, the elevator-base may be lowered so as to rest on the posts f , g , and the wheels m , n , raised.

We claim:

65 1. A portable elevator including a base;

legs upon which the same may be supported; a steering-wheel; a steering-wheel carrier pivotally mounted on said base; and an operating-arm which is rotatably mounted on said carrier and free from connection with 70 said base; said operating-arm being arranged to be swung with said carrier to throw the steering-wheel into contact with the floor and then to be turned on said carrier to lock the same in position with the 75 steering-wheel in rolling contact with the floor.

2. A portable elevator including a base; legs upon which the same may be supported; a steering-wheel; other wheels for supporting said base; means for throwing said other wheels into contact with the floor; a steering-wheel carrier pivotally mounted on said base and operatively connected with said means; and an operating-arm which is 80 rotatably mounted on said carrier and is free from connection with said base; said operating-arm being arranged to be swung with said carrier to throw the steering-wheel and the other wheels into contact with the 85 floor and then to be turned on said carrier to lock the same in position with the wheels in rolling contact with the floor.

3. A portable elevator including a base; legs upon which the same may be supported; 90 eccentrics rotatably mounted on said base; wheels upon which said base may be supported when said legs are raised from the floor and which are mounted upon said eccentrics; a crosspiece pivotally mounted on said base; means for rotating said eccentrics to raise and lower the wheels mounted thereon, said means being operated by said crosspiece; and an operating-arm by which said crosspiece is swung and said means are 95 caused to rotate said eccentrics to bring said wheels into rolling contact with the floor and to raise said legs therefrom.

4. A portable elevator including a base; legs upon which the same may be supported; 100 eccentrics rotatably mounted on said base; wheels which are mounted upon said eccentrics and upon which said base may be supported, when said legs are raised from the floor; a crosspiece pivotally mounted on said base; means for rotating said eccentrics to raise and lower the wheels mounted thereon, said means being operatively connected with said crosspiece; an operating-arm by which said crosspiece is 110 swung and said means are caused to rotate said eccentrics to bring said wheels into rolling contact with the floor and to raise said legs therefrom; and means for locking said crosspiece in position.

5. A portable elevator including a base; legs upon which the same may be supported; 115 eccentrics rotatably mounted upon said base; wheels which are mounted upon said eccentrics and upon which said base 120

may be supported, when said legs are raised from the floor; a crosspiece pivotally mounted on said base; means for rotating said eccentrics to raise and lower the wheels mounted thereon, said means being operatively connected with said crosspiece; an operating-arm by which said crosspiece is swung and said means are caused to rotate said eccentrics to bring said wheels into contact with the floor and raise said legs out of contact therewith; and means for limiting the swing of said crosspiece and the resulting throw of said eccentrics.

6. A portable elevator including a base; legs upon which the same may be supported; eccentrics rotatably mounted upon said base; wheels which are mounted upon said eccentrics and upon which said base may be supported, when said legs are raised from the floor; a crosspiece pivotally mounted on said base; a steering-wheel carried by said crosspiece; means connecting said crosspiece operatively with said eccentrics, whereby said eccentrics are turned by swinging said crosspiece; and an operating-arm by which said crosspiece is swung and said eccentrics are turned to throw said wheels into rolling contact with the floor and to raise said legs out of contact therewith.

7. A portable-elevator base of the type having legs and wheels, including a front wheel, upon which legs and wheels the base

may be alternately supported, characterized in that the front wheel is mounted upon a swinging carrier; the other wheels are mounted to rotate upon eccentrics; and the carrier is operatively connected with the latter and, when swung, throws the front wheel into and out of contact with the floor and turns the eccentrics to lower and raise the other wheels into and out of contact with the floor and support the base alternately upon the wheels and the legs.

8. A portable-elevator base of the type having legs and wheels, including a front wheel, upon which legs and wheels the base may be alternately supported, characterized in that one of the wheels is mounted upon a swinging carrier which is swung by an operating arm; and the latter is mounted in the carrier rotatably and free from connection with the base and may be thrown with the carrier to force the wheel carried thereby into contact with the floor and then turned on the carrier into locking engagement with the base.

Signed at Jersey City, county of Hudson and State of New Jersey, this twenty-second day of June, A. D. 1918, in the presence of the two undersigned witnesses.
